US00D995632S

(12) **United States Design Patent** (10) **Patent No.:** **US D995,632 S**
Wang (45) **Date of Patent:** **** Aug. 15, 2023**

(54) **TARGET BOARD**

(71) Applicant: **AUTEL INTELLIGENT TECHNOLOGY CORP., LTD.**,
Guangdong (CN)

(72) Inventor: **Yongshuai Wang**, Guangdong (CN)

(73) Assignee: **AUTEL INTELLIGENT TECHNOLOGY CORP., LTD.**,
Guangdong (CN)

(**) Term: **15 Years**

(21) Appl. No.: **29/756,133**

(22) Filed: **Oct. 26, 2020**

(30) **Foreign Application Priority Data**

Apr. 27, 2020 (CN) 202030180452.9

(51) **LOC (14) Cl.** **21-01**

(52) **U.S. Cl.**

USPC **D21/302**

(58) **Field of Classification Search**

USPC D21/300-307, 319, 335, 312, 322, 324,

Primary Examiner — Mehri F Bajoul

(57) **CLAIM**

I claim the ornamental design for a target board, as shown and described.

DESCRIPTION

FIG. 1 is a front elevational view of a target board showing my new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

1 Claim, 2 Drawing Sheets
